FIG. VII

UNITED STATES PATENT OFFICE

JAMES A. JENSEN, OF PHILADELPHIA, PENNSYLVANIA, ASSIGNOR TO QUAKER CITY IRON WORKS, OF PHILADELPHIA, PENNSYLVANIA, A CORPORATION OF PENNSYLVANIA

GRAVE VAULT

Application filed June 26, 1931. Serial No. 547,030.

This invention relates to grave vaults; and it has reference more particularly to metallic grave vaults of the type wherein one end is open for introduction of the 5 burial casket.

Considered in its broadest aspect, my invention is directed toward provision of simple, reliable and efficient locking mechanism whereby the doors for the end openings of 10 vaults of the type specifically referred to, may be effectively locked with assurance of a perfect seal all around to preclude ingress of moisture.

Another object of my invention is to afford, in connection with vault locking mechanism having the above indicated attributes, automatically operative latch means adapted, incident to closure of the vault door at the time of interment, to permanently 15 secure the locking mechanism against subsequent actuation.

Still other objects and attendant advantages of this invention will be manifest from the following detailed description of the 20 attached drawings, wherein Fig. I is a side elevation of a grave vault embodying the present improvements.

Fig. II is an elevation of the right hand end (as considered in Fig. I) of the vault. 25 Fig. III is a cross sectional view on a larger scale, taken as indicated by the arrows III—III in Fig. I, showing the end door of the vault closed and locked.

Fig. IV is a fragmentary sectional view, 30 taken as indicated by the arrows IV—IV in Fig. III, and drawn to a larger scale.

Figs. V and VI are fragmentary detail sectional views taken as, respectively, indicated by the arrows V—V and VI—VI in 35 Fig. III.

Fig. VII is a cross sectional view of the vault, like Fig. III, but with the locking mechanism in unlocked position.

Fig. VIII is a fragmentary view on a 40 still larger scale, featuring, more particularly, the latch means whereby the locking mechanism is permanently secured after the vault door is closed at the time of burial.

Fig. IX is a detail sectional view taken 45

as indicated by the arrows IX—IX in Fig. VIII; and

Fig. X is a view similar to Fig. IX, but with a keeper of the latch removed to permit the latter to function. 55

The grave vault herein illustrated has a body 1 which is constructed from sheet metal with straight bottom and side walls 2, 3 and 4, and with an arched top 5. The left hand end (Fig. I) of the body 1 is 60 closed by a wall 6 which is permanently united to the bottom 2, the sides 3, 4 and the top 5 by riveting or welding; but the opposite or right hand end of said body is open to enable introduction of the burial 65 casket (not shown) and provided with a closure in the form of a door 7. This door 7 is supported along one of its side edges by hinges 8 comprising components 9 and 10 which are respectively secured to the door 70 and the body 1. From Fig. IV it will be noted that the pintles 11 of the hinges 8 snugly fit the bosses of the hinge components 9 on the door, and pass through elongated apertures 12 in the ears of the companion components 10. This construction 75 obviously permits a certain amount of lost play in the hinges 8, which is essential for a purpose later on explained. After common practice, the vault body 1 is equipped 80 with suitable lift handles 13, 14, 15 and 16, along opposite sides and ends.

Referring again to Fig. IV, it will be observed that the door 7 closes against a compressible gasket 17 which is lodged in a recess afforded by a perimetric angular flange member 18 set into the open end of the vault body 1 and united to the walls of the latter by over edge welding as indicated conventionally at 19. 85 90

The novel mechanism which I have devised for locking the vault is carried on the back of the door 7, and as shown in Figs. III, IV and VII comprises four locking elements 20, 21, 22 and 23. At their outer ends, 95 these locking elements 20, 21, 22 and 23 are, respectively, provided with bolt projections 20a, 21a, 22a and 23a having guidance in correspondingly spaced apertures of angle bars 24, 25, 26 and 27 secured to the 100

door 7 adjacent the edges of the latter. At their inner ends, the locking elements 20—23 are formed with longitudinally open yoke shanks 20b, 21b, 22b and 23b, and from said shanks project lateral studs 20c, 21c, 22c and 23c. The studs 20c, 23c and 21c, 22c of the opposite locking elements 20, 23 and 21, 22 engage longitudinal guide slots 28, 29 respectively near the ends of a pair of crossed bridging straps 30 and 31. As shown, the foot portions 32, 33 of the bridging straps 30, 31 extend through the open yokes 20b—23b of the respective locking elements 20, 23 and 21, 22, and are secured to the back of the door 7. The actuating means for the door locking mechanism includes a disk 35 with oppositely projecting axially-aligned trunnions 36, 37. The trunnion 36 projects outward through an opening 38 in the door 7, and, as shown in Fig. IV, its protruding end is squared as at 39 for application of a wrench or other suitable operating implement. The inner trunnion 37 of the disk 35, on the other hand, has journal support at the intersection of the two bridging straps 30, 31, see Figs. III, IV and VII. The disk 35 is in the present instance held against axial shifting in the assemblage by means of cotter pins 40 and 41 engaging through the ends of its trunnions 36, 37. Adjacent its periphery, the disk 35 is provided with four equally-spaced laterally-projecting studs 42, which, through coupling links 43, are respectively coordinated with the studs 20c, 21c, 22c and 23c of the locking elements 20, 21, 22 and 23.

To lock the vault, the operating implement is applied at the exterior of the door 7 to the squared end 39 of the trunnion 36 of the disk 35, and turned to rotate the disk in the direction indicated by the arrow in Fig. VII. As a result, the four locking elements 20, 21, 22 and 23 are radially projected concurrently to the position shown in Fig. III, so that their bolt ends 20a, 21a, 22a and 23a engage behind the perimetric flange 18 adjacent the opening in the vault body 1. Now it will be particularly noted from Fig. IV, that the tips of the bolt ends 20a, 21a, 22a and 23a of the locking elements are beveled for wedging action with the flange 18 to draw the door 7 firmly against the compressible perimetric gasket 17, this action being permitted by virtue of the afore-described free play in the hinges 8. Thus, with locking of the door 7, the vault is effectively sealed against subsequent ingress of moisture. Incident to unlocking of the locking mechanism, the rotation of the disk 35 is limited through engagement of a stop lug 35a thereon with the bridging strap 30, as shown in Fig. VII.

To permanently secure the vault upon closure of the door 7 at the time of burial, I have provided an automatically operative

latch means 45 which is shown in detail in Figs. V, VI, VII, VIII, IX and X. This latch means 45 comprises a pivotal latch 46 which is swingable about a pin 47 engaging through a pair of confining ears 48 on the shank of one of the four locking elements—in this instance the locking element 23. The latch 46 is urged downwardly or in a direction away from the observer in Fig. VIII by a finger spring 49 whereof the coil encircles the pivot pin 47. To ordinarily prevent the latch 46 from functioning, a keeper in the form of a cotter pin 50 is passed through registering apertures on a pair of outstanding lugs 51 at the opposite side of the shank 23b of the locking element 23 to intercept the latch 46, as shown in Fig. IX, the said cotter pin being provided with a ring 52 for the purpose of quick and easy withdrawal. Upon removal of the cotter pin 50 with the locking mechanism in unlocked position, the latch 46 will be released to rest against the outer face of the strap 30 as in Fig. X. When the door 7 is finally closed and the locking mechanism actuated at the time of interment, the latch 46 will slide along the bridging strap 30 incident to movement of the locking element 23, and will be ultimately thrust, by its spring 49, behind the shoulder end 53 of the said strap as in Figs. III, V, IV and VIII. With this accomplished, it is evident that the vault door 7 is not only securely locked and sealed, but the locking mechanism itself permanently secured against the possibility of being actuated thereafter.

Having thus described my invention, I claim:

1. In a grave vault including a body open at one end to receive a burial casket and having a perimetric angular flange set into said open end; a hinged door to close the opening, and locking mechanism at the back of the door comprising radially-slidable members with outward bolt projections to respectively engage the angular flange, and also embodying inward longitudinally open yoked shanks, apertured angle bars on the door to guide the bolt projections of the said members, crossed bridging straps also on the door to engage the longitudinal openings in the shanks of the said members; and means whereby the locking mechanism can be operated from the exterior of the vault.

2. In a grave vault including a body open at one end to receive a burial casket and having a perimetric angular flange set into said open end; a door to close the opening, and locking mechanism at the back of the door comprising radially-slidable locking members with outward bolt projections for engaging the angular flange, said locking members having longitudinally-open yoked shanks, crossed bridging straps with foot portions secured to the inside and reaching

through the longitudinal openings in the yoke shanks of the locking members, and an actuating element for the locking members rotatably journaled at the juncture of the 5 bridging straps.

3. In a grave vault including a body open at one end to receive a burial casket and having a perimetric angular flange set into said open end; a door to close the opening, and locking mechanism at the back of the door, 10 operable from the exterior of the vault, comprising radially-slidable locking members with outward bolt projections to respectively engage the angular flange, said locking members having longitudinally open yoked shanks, bridging straps secured to the door and having their foot portions reaching through the longitudinal openings in the shanks of opposite pairs of the locking members, studs on the locking members engaging guide slots in the bridging straps, and an actuating element for the locking members 15 rotatably journaled at the juncture of the bridging straps.

25 4. In a grave vault including a body open at one end to receive a burial casket and having a perimetric angular flange set into said open end; a door to close the opening, and locking mechanism at the back of the door, 30 operable from the exterior of the vault, comprising radially-slidable locking members with outward bolt projections and longitudinally-open yoked shanks, bridging straps secured to the door having their foot portions reaching through the longitudinal 35 openings in the shanks of opposite pairs of the locking members, studs on the locking members in engagement with guide slots in the bridging straps, an actuating element rotatably journaled at the juncture of the two 40 straps, and coupling links connecting the studs on the locking members with the rotary actuating element.

5. In a grave vault including a body open 45 at one end to receive a burial casket and having a perimetric angular flange set into said open end; a door to close the opening, and locking mechanism at the back of the door, operable from the exterior of the vault, 50 comprising a slidable locking member with outward bolt projections having bevelled portions for engaging at the back of the angular flange, a spring influenced latch pivoted on the locking member adapted, as the 55 latter is shifted into locking position, to automatically engage a fixed part on the door, thereby to render the enclosure permanent, and a split cotter passing through registering apertures of lugs projecting from 60 the locking member in the path of movement of the pivoted latch, designed for removal at the time of burial, to normally prevent functioning of the latch under the action of the spring.

65 6. In a grave vault including a body open

at one end to receive a burial casket and having a perimetric angular flange set into said open end; a door to close the opening, and locking mechanism on the back of the door, 70 operable from the exterior, comprising radially guided locking members having outward bolt projections for coaction with the flange aforesaid and longitudinally-open yoked shanks, crossed bridging straps having their foot portions secured to the door and reaching through the longitudinal openings in the yoke shanks of opposite pairs of locking members, and a pivoted latch on one of the locking members, adapted, as the locking mechanism is operated, to automatically 75 drop over the end of the corresponding strap, thereby to render the closure permanent.

In testimony whereof, I have hereunto signed my name at Philadelphia, Pennsylvania, this 19th day of June, 1931.

JAMES A. JENSEN.
